UNITED STATES PATENT OFFICE.

HENRY MÜLLER, OF WATERBURY, CONNECTICUT.

EMERY-CLOTH HOLDER.

1,394,757.

Specification of Letters Patent. Patented Oct. 25, 1921.

Application filed March 17, 1921. Serial No. 453,106.

To all whom it may concern:

Be it known that I, HENRY MÜLLER, a citizen of the United States, residing at Waterbury, in the county of New Haven and State 5 of Connecticut, have invented a new and useful Improvement in Emery-Cloth Holders; and I do hereby declare the following, when taken in connection with the accompanying drawings and the characters of reference marked thereon, to be a full, clear, 10 and exact description of the same, and which said drawings constitute part of this application, and represent, in—

Figure 1 a side view of an emery-cloth holder constructed in accordance with my 15 invention.

Fig. 2 a vertical sectional view of the same.

Fig. 3 an inside plan view of the two members separated and partly in section to illustrate the clamping of the abrasive material thereto.

Fig. 4 a transverse sectional view on the line 4—4 of Fig. 2.

Fig. 5 an inside plan view of the two block 25 members, with the clamps removed.

Fig. 6 a perspective view of one of the clamp-plates detached.

Fig. 7 a perspective view of one of the clamps detached.

Fig. 8 a perspective view of one of the clamp-cams detached.

Fig. 9 a side view of a key for operating the cam.

Fig. 10 a perspective view of the nut-plate 35 detached.

Fig. 11 a perspective view of the end-plate detached.

Fig. 12 a broken view, partly in plan and partly in section, of a modified form of my 40 invention.

This invention relates to an improvement in emery-cloth holders and particularly to holders which are adapted to hold a strip of emery-cloth, the object being to provide a 45 rectangular body around which the cloth may be folded, so as to present four working faces, and so construct the holder that the cloth may be readily applied and removed and firmly held when applied, and the invention consists in the construction and arrangements of parts as hereinafter described and particularly recited in the claims.

In carrying out my invention I employ 50 two holding-blocks 15 and 16, corresponding in shape and adapted, when brought together, to provide a rectangular block of the

desired dimensions. The inner faces of these blocks are formed respectively with centrally-arranged longitudinal grooves 17 and 18, and near one side with longitudinal 60 grooves 19 and 20. At intervals the inner faces of these blocks are formed with recesses 21, for the purpose as will hereinafter appear, and the opposite ends are cut away to form chambers 22 having beveled edges. 65 In each of the recesses 21 I locate a plate 23, having an upstanding-flange 24 along the line of the outer edges of the grooves 19. Resting upon the plate 23 are clamping-members 25, formed with flanges 26, adapted to 70 stand parallel with the flanges 24 and provided with a clearance-slot 27, and a post 28. Superimposed upon the clamp 25 and riveted to the plate 23 is a cam 29, provided with a slot 30, through which the post 28 75 projects and provided with perforations 31 for the reception of a key 32, by which the cam 29 may be turned. The handle 33 is formed with a long spindle 34, adapted to enter the longitudinal grooves 17 and 18, 80 extending through eyes 35 and 36 mounted in the respective blocks, and whereby the two blocks are connected together by the spindle. The spindle enters through an end-plate 37, and is threaded at its outer end for 85 engagement with a nut-plate 38 at the outer end. A strip of emery-cloth 39, or other abrasive material, of suitable width and length, is folded about the two members, which are then opened and the edges of the 90 cloth are turned inward between the flanges 24 and 26, and the cam 29 is then turned so as to crowd the flange 26 against the abrasive material and against the flange 24. With the material thus secured, the handle-spindle is 95 inserted so as to interlock the two block-members, and, if desired, a spring 40 may be applied around the spindle, between the end of the handle and the end-plate 37, which will tend to force the handle outward 100 when it is released from the nut-plate 38, and, if desired and as shown, the plates 37 and 38 may each be provided with a dowel-pin 41, adapted to enter holes 42, formed for them in the beveled ends of the blocks. If 105 desired the two blocks may be provided with alined pockets 43 for the reception of the key 32.

While I prefer to employ the plate 23, with its flange 24, it is obvious and as shown 110 in Fig. 12 of the drawings that this plate may be omitted, and the edge of the abrasive

material clamped by the flange 26 against the edge of the grooves 19 and 20. Also, as shown in this figure, instead of employing the post 28 and slot 30, a cam may be formed 5 with a cam-face 43 to force the flange 26 outward.

It will be seen that when assembled the holder presents four wearing surfaces, and the abrasive material is so firmly held that 10 it cannot accidentally be torn away from the holder, and the abrasive material is readily applied and removed, as desired.

I claim:

1. An emery-cloth holder, consisting of 15 two uniform block-members, each formed with a centrally-arranged longitudinal groove, clamps mounted in each member and adapted to clamp the opposite edges of a strip of abrasive material, eyes mounted on 20 the respective members, a spindle adapted to pass through said eyes, whereby the two block-members are connected together and a handle applied to said spindle.
2. An emery-cloth holder comprising two 25 block-members, each formed with a centrally-arranged longitudinal groove, and with a groove parallel therewith, and each member formed with a series of recesses, a clamp-member mounted in each of said recesses, a cam connected with the clamp-member and adapted to force them outward, and means for connecting the two block-members 30 together.
3. An emery-cloth holder comprising two 35 block-members, each formed with a cen-

trally-arranged longitudinal groove, and each formed with a groove parallel therewith, and each formed with a series of recesses, plates mounted in said recesses and formed with flanges, clamps superimposed upon said plates, cam-members connected with said plate and adapted to move said clamps, and means, including a handle-spindle, for connecting the two block-members together. 40

4. An emery-cloth holder comprising two block-members, each formed with a centrally-arranged longitudinal groove, and each formed with a groove parallel with the central groove, the ends of the blocks recessed and the inner faces each formed with a series of recesses, clamps arranged in the said recesses and co-acting to hold the edges of a strip of abrasive material, a series of eyes mounted in said block-members, a handle and a handle-spindle adapted to extend through the grooves 17 and 18 and through the said eyes, whereby the two block-members are connected together, an end-plate for the inner ends of the block-members, and a nut-plate for the outer ends of the block-members and with which the handle-spindle engages. 50

In testimony whereof I have signed this specification in the presence of two subscribing witnesses. 65

HENRY MÜLLER.
